UNITED STATES PATENT OFFICE.

JOHN F. BURROUGHS, OF BALTIMORE, MARYLAND, ASSIGNOR TO T. R. GOODLATTE & SONS, INC., OF DELAWANNA, NEW JERSEY, A CORPORATION OF NEW JERSEY.

DESIGN FOR A TABLE COVER OR ANALOGOUS ARTICLE.

Application filed November 23, 1925. Serial No. 15,519. Term of patent 7 years.

To all whom it may concern:

Be it known that I, JOHN F. BURROUGHS, a citizen of the United States, residing at Baltimore, in the county of Baltimore and State of Maryland, have invented a new, original, and ornamental Design for a Table Cover or Analogous Article, of which the following is a specification, reference being had to the accompanying drawing, forming part thereof.

The figure is a plan view of a table-cover,

showing my new design, partly in full lines and partly in outline, the parts shown by full lines, with exception of the center figure, being repeated in diametrically opposite places in the parts of the design shown in outline.

I claim:

The ornamental design for a table-cover or analogous article, substantially as shown and described.

JOHN F. BURROUGHS.
